Sheffield & Bette.

UNITED STATES PATENT OFFICE.

EUGÈNE FRANÇOIS SUTER, OF PICCADILLY, LONDON, ENGLAND.

PERMANENT HAIR WAVING.

Application filed March 15, 1922. Serial No. 543,979.

To all whom it may concern:

Be it known that I, EUGÈNE FRANÇOIS SUTER, a citizen of Switzerland, residing at 23 Grafton Street, Piccadilly, London, W., 5 England, have invented certain new and useful Improvements in Permanent Hair Waving, of which the following is a description.

This invention relates to improvements in or connected with permanent hair waving 10 whereby the appearance of naturally wavy hair is produced, and more particularly is maintained in hair which has been previously permanently waved.

In the known process of permanently waving human hair a tress of hair is tightly wound upon a curler, which is preferably provided with means for tightening the coils after they have been wound, moisture or a moist pad is applied to the wound tress, and 20 the whole is completely enclosed in a capsule and heated. Hitherto the moisture, usually in the form of a lotion, has been put on to the hair or into the capsule, or a moist pad, usually containing a large proportion 25 of borax, has been wound on to the hair or attached to the inside of the capsule, and in all such cases the steam or vapour produced when the heat is applied has been able to circulate inside the capsule and to reach all 30 parts of the tress.

It is well known that human hair grows out from the head at the rate of about half an inch a month and that when the process of permanently waving is repeated, which is 35 usually done about every six months, there is a length of hair near the root end of each tress which has never been waved before, while the rest of the tress should not need re-waving at all. I have found that the common practice of tightening the coils only at 40 the root end of the tress and of applying the heat only at the end of the capsule containing the root end of the tress does not prevent the other end of the tress being re-waved so long as the steam or vapour produced inside the capsule can reach all parts 45 of the tress. Moreover the frequent waving of the same length of hair tends to make it brittle and frizzy at the tips.

According to this invention I cover the tress, after it is wound and tightened upon the curler and before the moist pad is applied, with a layer of impervious material which is perforated in an irregular manner, 50 and I prefer also to cover the moist pad 55 after it is applied with another layer of im-

pervious material which is not perforated, so that, when the whole is enclosed in a capsule and heated, the steam or vapour can only reach the tress at the parts and in the 60 quantities required to produce the appearance of naturally wavy hair. Instead of being in separate layers the edges of the two pieces of impervious material may be joined together with the borax pad between so as 65 to form a compound pad or sachet with an impervious exterior irregularly perforated on one side, which compound pad or sachet after being suitably moistened may be placed over the wound tress in a single operation 70 requiring less time and skill than the adjustment of separate layers.

I have found the substance known under the registered name of cellophane (which is an artificial oilsilk consisting of a transparent film of very fine cellulose) suitable as the impervious material; and the irregular perforation of the inner layer thereof may be arranged so as to vary in density from end 75 to end, but preferably consists of a small 80 area of dense perforations arranged to come at the root end of the wound tress and to extend along it for a distance depending upon the condition of the hair and the treatment required. Three of the edges of the impervious material are preferably made to extend considerably beyond the enclosed pad so as to overlap the longitudinal joint and 85 cover all the hair when the sachet is in position, and at the root end of the tress the edge 90 may advantageously extend beyond the curler as the impervious material helps to seal the capsule when the latter is tied down upon the extended edge instead of directly 95 upon the bare tress. The fourth edge of the 100 impervious material, which is the first applied to the wound tress and forms one side of the longitudinal joint when the sachet is in position, preferably does not extend beyond the enclosed pad and may conveniently be made by the fold in a single piece of impervious material which then forms both layers.

I now proceed to describe in detail and 105 by way of example the preferred form of sachet shown in the accompanying drawings, in which

Fig. 1 is a plan of a blank of impervious material adapted to be folded to form the outer covering of the sachet according to my 110 invention.

Fig. 2 is a plan of a pad, partly broken

away, for purposes of illustration, for use in the sachet according to my invention.

Fig. 3 is a plan, partly broken away for purposes of illustration, of a complete article according to my invention.

Fig. 4 is a section on the line 4, 4 of Fig. 3.

Figs. 5, 6 and 7 are views illustrating the process of treating the hair according to my invention and also illustrating the manner of using the sachet illustrated in Fig. 3.

In Figure 1 *ab* is a sheet of cellophane adapted to be folded along the line *dc* so as to form an inner layer *db* and an outer layer *ac* of impervious material, between which layers a pad *p* is placed. The inner layer *db* is perforated at *e* and its edges *dg* and *gb* (as indicated by the dotted lines) are folded over the pad *p* and gummed or otherwise attached to the outer layer *ac* to make the complete sachet shown in Fig. 3. The edge *bc* may also be folded over and gummed or otherwise closed, but this is unnecessary when the pad does not come near this edge, and the opening thus formed is convenient for the application of moisture to the pad. When the edge *bc* is not closed the pad *p* may be gummed to the impervious material in order to keep it in its proper position within the sachet as shown in Fig. 3, where it can be seen through the transparent cellophane. The pad *p* preferably consists of a flat rectangular bag of muslin or similar material containing the borax *px* or other substance with which the hair is to be treated, and is as large as or a little larger than the perforated area *e*.

The complete sachet A shown in Fig. 3 is of such a size that the length *dc* is greater than that of the tress when wound upon a curler *h* as illustrated in Figs. 5 and 6, and the length *dg* is about equal to the circumference of the wound tress, so that when rolled around the wound tress the part *gc* completely covers the same, and the part *ab* overlaps and covers the part *gc*. The perforated portion *e* is arranged to come at the root end of the wound tress and the part *ad* extends beyond the end of the curler

close up to the head forming two layers of 50 impervious material which greatly assist in sealing the capsule *i* (Figs. 6 and 7) when the latter is tied down upon this extension instead of upon the bare tress. Ordinarily I find also that the construction of sachet 55 disclosed herein permits me to omit the capsule *i* when desired I place a folded piece of paper *s* alongside the pad *p* beneath the inner layer *db* to prevent the pad *p* from being accidentally displaced from beneath 60 the perforations *e*. The use of the paper *s* is advantageous also in other ways which need not be enumerated in detail.

Having now particularly described and ascertained the nature of my said invention 65 and in what manner the same is to be performed I declare that what I claim is:

1. The process of permanently waving hair comprising covering the tress after it has been wound upon the curler and before 70 the application of any lotion or moist pad with a perforated layer of impervious material in order to protect part of the tress from the action of the moisture or of the vapour produced when the latter is heated 75 substantially as described.

2. In the process of permanently waving hair comprising covering the tress after it has been wound upon the curler firstly with a perforated layer of impervious material, 80 secondly with a moist pad, and thirdly with another layer of impervious material in order to protect part of the tress from the action of the moisture or of the vapour produced when the latter is heated substantially 85 as described.

3. In the process of permanently waving hair as claimed in claim 2 extending at least one layer of impervious material beyond 90 the end of the curler close up to the head in order to assist in sealing off the head from the part of the tress on the curler.

4. A sachet consisting of a pad within an impervious exterior irregularly perforated on one side for use in the process of permanently waving hair substantially as described.

EUGÈNE FRANÇOIS SUTER.

CERTIFICATE OF CORRECTION.

Patent No. 1,449,874.

Granted March 27, 1923, to

EUGENE FRANCOIS SUTER.

It is hereby certified that error appears in the printed specification of the above numbered patent requiring correction as follows: Page 2, lines 55 to 57, strike out "I find also that the construction of sachet disclosed herein permits me to omit the capsule i when desired" and insert the same before the word "Ordinarily" in line 54; and that the said Letters Patent should be read with this correction therein that the same may conform to the record of the case in the Patent Office.

Signed and sealed this 14th day of July, A. D. 1931.

(Seal)
